AMMUNITION CONTAINER

Joseph P. Stein, Los Angeles, Calif.

Application April 10, 1945, Serial No. 587,447

5 Claims. (Cl. 206—3)

1

The invention relates to containers, and more particularly to containers for ammunition and the like. The present application is in the nature of an improvement and continuation in part of my prior application, Serial No. 576,595, filed February 7, 1945, entitled Ammunition container, the entire disclosure of which is hereby incorporated by reference as part of the disclosure of the present application.

Such ammunition containers, in actual use, are subjected to varied weather conditions, as well as to severe strains in handling. Accordingly, before such containers are accepted by Governmental authorities they are generally subjected to rigid preliminary tests intended to prove the fitness of such containers to withstand the most rigorous conditions which may be met with in actual service. Both fiber and metal containers have been proposed, but both types of containers have certain disadvantages. Thus, the fiber containers, which are generally spirally wound, are likely to part at the junctures and the sharp ends are likely to be broken. Metal containers, on the other hand, become dented, making it difficult if not impossible to remove the projectile therefrom, and in some cases the metal casing is punctured.

One of the tests in common use consists in soaking a container for an extended period to determine its waterproofness, and this test is repeated after further tests of a mechanical nature, which will now be described.

Another test is to subject a pile of such containers to severe and extended vibration comparable to conditions on shipboard, the purpose being to determine the compactness of the package. After the vibrating test the container is opened to see whether the projectile and cartridge case are still retained in their original position.

A further test is to drop a loaded container on a steel plate in such manner that the edges of the container will contact the plate. Where the container possesses sharp edges this test usually so mars the container that it is no longer waterproof and is unfit for service.

A still further test is the drum test, wherein a container is placed in a revolving steel drum containing baffle plates and the container is subjected to repeated falls from a height of several feet to the hard bottom of the drum. In this manner all portions of the container are subjected to strains, the baffle plates within the drum adding to the severity of the test. The drum test is generally followed by an edge test such

2

as preceded the drum test, four of these tests being employed in succession. Since each drum test ordinarily involves twenty-four falls of the container the entire series of drum tests involves ninety-six falls, supplemented by the four edge falls.

One of the most severe tests is one known as the side drop, wherein a loaded container is dropped lengthwise upon a two-by-four set edge-wise upon a steel plate. It has been found that more than sixty-five per cent of the ordinary containers, both metal and fiber, tested in this manner fail to pass the test.

A further test for the container relates to its fireproofness, and in this connection fire is kindled under the container, or a pile of such containers, in order to determine the amount of heat which such container will withstand, and also to determine the inflammability of the surface coating.

The primary object of the present invention was accordingly to device an ammunition container which would withstand all required Government tests and which would stand up under service conditions. A further object was to produce an ammunition container which would be as inexpensive as possible consistent with strength, compactness, waterproofness and fireproofness. A further object was to do away with the use of wooden boxes or metal containers which are now in common use for enclosing fiber containers, both wood and metal being critical materials. Another object of the inventor was to provide an ammunition container which is light in weight and may be readily handled at the gun position. I have designed an ammunition container which complies with all of the above requirements, and which is composed of three inner fiber tubes, a projectile supporting tube, a projectile neck tube, and a cartridge case neck tube, which tubes are adapted to retain a projectile and cartridge case in axial alignment in accordance with present practice.

In accordance with the disclosure of my prior application these fiber tubes were telescoped within a body tube formed with inner layers of fiber completely protected with an outer covering of laminated, tough textile material, such as canvas reinforced with metal wire mesh netting. All of these layers were adapted to be spirally wound by the use of the same machinery. The layers were adhesively secured together with asphalt or other suitable material and the canvas was preferably impregnated with a waterproof-

ing and fireproofing composition, such as chlorinated paraffin or the like.

In accordance with my present improvement the body tube may be formed of flexible plastic material, either natural or synthetic, such as rubber, either natural or synthetic, or one of the recently developed synthetic resins, such as polyvinyl butyral. Among the synthetic rubbers may be mentioned Buna S, Buna N, Thiokol, butyl and neoprene. Buna S is at present the most readily available of these materials, but butyl and neoprene possess certain advantages by reason of their superior water and age resisting properties. These and other available flexible synthetic rubber-like plastics, together with their respective properties, are described in Modern Plastics, February 1945, under the heading "Synthetic rubbers," to which reference may be had for further description of these materials. The flexible plastic rubber-like material of which the body tube is formed may be and preferably is suitably reinforced by means of fabric and/or metal, preferably wire mesh netting reinforcement, so as to increase the strength and durability of the tube.

In accordance with the disclosure of my prior application, Serial No. 576,595, the outer body tube connects and partially covers the inner tubes but does not extend the full length of the inner tubes, which ends, in accordance with my prior disclosure, were covered by rounded caps which comprise an inner sleeve or cap of rubber-like material which fitted within an outer cover formed of fiber, and preferably formed of fiber and wire reinforced canvas. I have found that when a body tube composed of flexible plastic rubber-like material is employed in accordance with the present improvement I may likewise employ molded rubber-like caps similar to the inner sleeves or caps disclosed in my aforesaid application, Serial No. 576,595, but without the outer cover portion. These flexible end caps may be formed of the same material as the body tube and may be similarly reinforced. I have found that for most satisfactory results rubber-like materials of which the end caps and body tube are composed should have a barometer rating substantially in the range of 75 to 85.

Where a composite fiber and canvas body tube such as is disclosed in my prior application Serial No. 576,595 is employed each of the end covers preferably includes an inner sleeve of flexible rubber-like material, either natural or synthetic, and an outer cover of reinforced canvas such as is disclosed in my aforesaid application. I now find it desirable, however, in such case to form the inner sleeve or end cap with an external flange or bend which serves to reinforce the cap and also to provide an abutment for the end of the skirt portion of the composite cover, thereby increasing the strength and improving the moistureproof qualities of the container as a whole.

Another feature in common with my prior application resides in the use of a tapered ring member which is retained between the end of the rubber cap and the butt end of the projectile at one end of the container, for the dual purpose of supporting the rear end of the projectile and of strengthening the end cap at a portion where the container would otherwise be vulnerable to shock. The end caps are taped to the body portion and the whole may be coated with a suitable lacquer, preferably of olive drab color, which gives the entire casing a smooth appearance, as well as adding to the resiliency of the package as a whole. Such lacquer is preferably both waterproof and

fireproof. Where the fireproofing quality is of prime importance chlorinated paraffin or a cellulose acetate lacquer may be employed. Where drying speed is essential a nitro-cellulose lacquer may be substituted.

The invention will be more readily understood by reference to the accompanying drawing and the following detailed description, in which a preferred embodiment of the invention is set forth by way of illustration but not by way of limitation.

In the drawings:

Fig. 1 is a longitudinal sectional view partly in elevation of a loaded and closed ammunition container, a projectile and cartridge case being shown enclosed therein and represented in dotted lines;

Fig. 2 is a longitudinal section of the container, the caps being shown partially removed;

Fig. 3 is a sectional view of the container including the inner fiber tubes and the outer body tube, the end caps being entirely removed;

Fig. 4 is a section on line 4—4 of Fig. 1 on a larger scale;

Fig. 5 is a section on line 5—5 of Fig. 1 on an enlarged scale;

Fig. 6 is a plan view of the metal reinforced molded rubber washer or partition which separates the container into two compartments;

Fig. 7 is a section on line 7—7 of Fig. 6;

Fig. 8 is a section showing the metal reinforcing ring of the partition;

Fig. 9 is a fragmentary sectional view of a portion of the partition illustrating a step in the molding operation;

Fig. 10 is a longitudinal sectional view of one of the end caps with the portions broken away to show the reinforcing thereof;

Fig. 11 is a sectional longitudinal view of an improved end cap or inner sleeve for use with the reinforced canvas container disclosed in my prior application Serial No. 576,595;

Fig. 12 is a fragmentary sectional view showing such end cap applied to the container and including the outer reinforced canvas cover; and

Fig. 13 is a longitudinal sectional view showing a modified form of end cap for use with containers having rubber-like body tubes, the wire reinforcing being omitted in this type of cap.

Referring to the drawings, and particularly Fig. 1 thereof, the complete ammunition container is shown at A, the entire outer surface, including both body and end caps, being of rubber-like material and the end caps being rounded at A' to prevent breakage.

The container A is made up of a body portion B having reduced ends or neck portions C over which end caps D are adapted to be fitted after a projectile E and cartridge case F have been inserted from opposite ends of the body portion B. A cap reinforcing and projectile supporting ring G is fitted over the rear end of the projectile and when the cap D is applied at the projectile end of the container an internal shoulder on the cap abuts against the ring G and holds the same firmly in place. The interior of the container is separated into projectile containing and cartridge case containing compartments H and I, respectively, by means of a rubber coated partition K herein shown of an inner ring of metal completely covered with rubber-like material, which partition is centrally apertured so as to provide a support for the nose of the projectile, the end portion of which projects through the opening in the partition into the hollow end of

the cartridge case. The body portion B of the container includes three inner fiber tubes, namely a projectile neck tube 10, a projectile supporting tube 11, and a cartridge case 12. In addition there is provided an outer cover or body tube 13 composed of rubber-like plastic material, either natural or synthetic, preferably reinforced by a combination of fabric and wire mesh netting indicated generally at 14. The projectile neck tube 10 and the cartridge case neck tube 12 are of the same outer diameter and of the same length and are adapted to be inserted from opposite ends of the cover or body tube 13 and are adhesively secured thereto, being separated by the partition K which is centrally located with respect to the cover 13. The projectile supporting tube is shorter and of less diameter than the tubes 10 and 12 and fits within the tube 13, being spaced from the rear end thereof, and when assembled abutting the partition K at the reinforced portion thereof. The projectile neck tube 10 is provided with a metal rim 16 at the outer end thereof, while the cartridge case neck tube 12 is provided with metal rims 17 at each end thereof.

The partition K, shown in detail in Figs. 6 and 7, comprises an inner metal ring 18 completely covered with rubber or rubber-like material 19. To assist in the molding operation the metal ring 18 is provided with a series of openings 100 through which are initially inserted pins 101 to insure proper spacing of the metal ring within the mold and thus insure the proper thickness of the rubber coating. It will be noted that the completed partition includes a peripheral portion 103 extending beyond the perimeter of the metal ring 18, thus providing flexible contact portions for the fiber tubes 10 and 12, while the tube 11, as previously described, abuts the partition in alignment with the metal reinforced portion thereof. The partition K is provided with a central opening 20 which provides a guide and support for the nose of the projectile while the washer itself provides resiliency within the cartridge case.

The cap reinforcing and projectile supporting ring G is preferably of metal and comprises a body portion 21 having a radial flange 22 and a tapered inner face 23 surrounding the central opening, the tapered portion 23 conforming to the taper of the rear end of the projectile E. The radial flange 22 is adapted to fit between a shoulder 24 on the interior of the cap D and the metal rim 16 on the projecting end of the projectile neck tube 10.

In assembling the container the projectile neck tube 10, with the inserted projectile supporting tube 11 adhesively secured thereto, and the cartridge case neck tube 12 are inserted within the cover or body tube portion 13 from opposite ends thereof with the partition K at the center, the inner ends of the tubes 10 and 12 abutting at the rim portion 103 of the partition or washer K and the inner end of the tube 11 abutting the washer at the reinforced portion thereof. Equal portions of the projectile neck tube and cartridge case neck tube extend beyond the cover to provide the reduced neck portions C, C. The various tubes are adhesively secured together, preferably by means of suitable waterproof adhesive. The projectile E with the cap reinforcing and projectile supporting ring applied to the rear end thereof is inserted in the container from the left, as shown in Fig. 1, with the nose projecting through the central opening 20 and abutting

against the metal ring 19. Similarly, the cartridge case E is inserted into the tube 12 until the flange or rim 25 of the cartridge case rests against the outer rim 17 at the end of the tube. The inner end 26 of the cartridge case will then be spaced slightly away from the edge of the inner metal rim 17, thereby preventing contact between the same. The outer caps D are then fitted over the necks C with the shoulder 24 of one cap boring against the flat face of the cap reinforcing and supporting ring G and holding the same snugly on the projectile and in contact with the end of the tube 10. Similarly the shoulder 24 on the opposite cap abuts against the rim 25 at the end of the cartridge case E and accordingly no ring G is required at this point. Sealing tape 26', 26'' is then applied over the joints between the caps D and the body member B.

In common with the disclosure of my prior application Serial No. 576,595 end caps D, together with the projectile supporting and cap reinforcing ring G constitute important features of my invention.

In accordance with the preferred embodiment of my invention, as best shown in Figs. 1, 2 and 10, each end cap D is composed of molded rubber-like material 70 suitably reinforced by composite fabric and wire mesh material 71. Each end cap comprises a relatively thick head portion 72, a skirt portion 73, and a rounded edge 74 connecting the head and skirt portions. The cap is provided with an interfitting annular shoulder 24, the function of which, as previously described, is to abut against the outer face of the cap reinforcing and projectile reinforcing ring G. The reinforcement of the cap is desirable where the same is to be used without a canvas cover, this being particularly true of the skirt portion, though the reinforcing may be omitted from the head portion if desired, or where a sufficiently strong material is employed the reinforcement may be omitted entirely, as shown in Fig. 13, although ordinarily such reinforcement is employed except where the rubber cap is to be used with an outer cover as disclosed in my prior application Serial No. 576,595. When so used the cap is preferably provided with a bead 75 such as is shown in the form of cap included in Figs. 11 and 12. Over this cap a reinforced cover 76 is adapted to be applied composed of fiber and reinforced canvas as set forth in my application Serial No. 576,595. When the composite cap is assembled upon a container, as indicated in Fig. 12, the sleeve portion of the composite cover 76 abuts against said bead while the composite body tube B' composed of fiber and reinforced canvas layers 77 and 78 abut against the outer end of the bead. Thus a waterproof joint is insured.

In some cases it may be desired to suitably color the container, which may be accomplished either by coating or by the incorporation of a pigment within the material itself, or in other cases an envelope of camouflage material may be employed to encase the entire container so as to camouflage the same and cause the container to blend with the surroundings.

When the container is fully completed it may receive a spray coating of aceto-butyral or other fire resisting material such as the chlorinated hydrocarbons or other coating materials such as disclosed in my prior application, Serial No. 576,595.

In order to provide a smooth exterior for the completed container the tape 26', 26'' is preferably countersunk as indicated in the drawings.

The invention has been described in detail for the purpose of illustration but it will be obvious that numerous modifications and variations may be resorted to without departing from the spirit of the invention.

While the invention has been particularly described with reference to ammunition containers it will be obvious that many of the features of the invention are of broader application and may be used in other connections.

I claim:

1. A cylindrical container comprising an outer body tube member and a pair of inner tubular members fitting within said outer tube and extending beyond the ends thereof to form reduced end members adapted to receive end caps, and a partition interposed between said inner tubular member serving to divide the container into two compartments, said partition comprising a metal ring having a rubber casing molded thereabout and completely enclosing the metal ring.

2. A cylindrical container comprising an outer body tube member and a pair of inner tubular members fitting within said outer tube and extending beyond the ends thereof to form reduced end members adapted to receive end caps, and a partition interposed between said inner tubular member serving to divide the container into two compartments, said partition comprising a metal ring having a rubber casing molded thereabout and completely enclosing the metal ring, the outer tube being formed of rubber-like material.

3. A cylindrical container comprising an outer body member and a pair of inner tubular members fitting within said outer tube and extending beyond the ends thereof to form reduced end members adapted to receive end caps, and a partition interposed between said inner tubular member serving to divide the container into two compartments, said partition comprising a metal ring having a rubber casing molded thereabout and completely enclosing the metal ring, the outer

10 tube being formed of metal reinforced rubber-like material.

4. In combination with an outer tubular member, a pair of inner tubes fitting within said outer member with their ends projecting beyond the same to provide reduced neck portions for said container, and a partition member interposed between said inner tubes comprising a rubber covered ring against which the ends of the inner tubes abut.

5. In combination with an outer tubular member, a pair of inner tubes fitting within said outer member with their ends projecting beyond the same to provide reduced neck portions for said container, a partition member interposed between said inner tubes comprising a rubber covered ring against which the ends of the inner tubes abut, and caps fitting over said neck portions.
